DESIGN FOR A VACUUM CLEANER NOZZLE-
BRUSH UNIT OR SIMILAR ARTICLELurelle V. A. Guild, Darien, Conn., assignor to
Electrolux Corporation, New York, N. Y., a cor-
poration of Delaware

Application July 21, 1942, Serial No 107,634

Term of patent 14 years

(Cl. D9—2)

To all whom it may concern:

Be it known that I, Lurelle V. A. Guild, a citizen of the United States of America, residing at Ring Road, Darien, in the county of Fairfield and State of Connecticut, have invented a new, original, and ornamental Design for a Vacuum Cleaner Nozzle-Brush Unit or Similar Article, of which the following is a specification.

Referring to the drawing forming a part of this specification,

Fig. 1 is a plan view of a vacuum cleaner nozzle-brush unit showing my new design;

Fig. 2 is a front elevational view thereof; and
Fig. 3 is a side elevational view thereof.

The essential features of the design reside in the configuration and appearance of the body portion of the unit shown in full lines, and of these features the most important is the arrangement of the steps or shoulders formed over the top of the body portion on either side of the mid-section thereof and indicated on the drawing by

the reference character S. It will be noted from Figs. 1 and 2 that the planes of the steps on the sides of the body are inclined to the bottom surface of the latter so that the portions of the steps nearer the top of the body are nearer to the center than the portions of the steps at the bottom of the body. This design tends to concentrate the visual attention of an observer on the center of the unit where it is higher and wider so that he is less aware of the narrow thin end portions thereof. For the same purpose of drawing the observer's attention away from the ends of the unit, it will be seen in Fig. 3 that although the height of each step is the same, the vertical distance between the steps increases towards the top and center of the body.

I claim:

The ornamental design for a vacuum cleaner nozzle-brush unit or similar article, as shown and described.

LURELLE V. A. GUILD.
